L. HIRSCHBERG.
COVER FOR LAUNDRY TUBS.
APPLICATION FILED NOV. 8, 1920.

Patented July 18, 1922.

UNITED STATES PATENT OFFICE.

LEO HIRSCHBERG, OF NEWARK, NEW JERSEY.

COVER FOR LAUNDRY TUBS.

1,423,215.

Specification of Letters Patent. Patented July 18, 1922.

Application filed November 8, 1920. Serial No. 422,556.

To all whom it may concern:

Be it known that I, LEO HIRSCHBERG, a citizen of Russia, residing at Newark, in the county of Essex, State of New Jersey, have invented certain new and useful Improvements in Covers for Laundry Tubs; and I do hereby declare the following to be a full, clear, and exact description of the invention, such as will enable others skilled in the art to which it appertains to make and use the same.

This invention relates to tops for laundry tubs and it has for its object to provide an article of this character that will completely cover the opening of the tub, that will be held securely against accidental displacement horizontally in all directions and which nevertheless may be freely lifted from place when it is to be removed. It is a further object of the invention to provide an article of manufacture that will appeal to the manufacturer because of its facility and consequent economy of production, as well as appealing to the user by reason of both its efficiency and its durability. The durability is augmented by the formation of the doubled marginal portion and by the further formation integral, of the retaining flange.

30 In the drawings:

Figure 1 is an inverted perspective view of a cover embodying the present invention.

Figure 2 is a section taken vertically through the upper portion of a laundry tub and through the present top or cover, illustrating the manner of forming the doubled marginal portion and the flange integral and the arrangement of a cross brace in a durable manner.

40 Figure 3 is a vertical section taken from front to back through the upper portion of the laundry tub equipped with the present cover, the cover being in raised position and being partly in section to show the arrangement of the retaining chain.

Referring to the drawings, there is shown a portion of a common type of laundry tub 10, which as is well known is usually constructed of soap stone, concrete, slate or other similar material, the upper edge of each wall of a tub of this character, having considerable transverse extent.

When the tub is not in use, it is desirable that it be covered in such manner as to conceal the unsightliness of its interior, to pre-

serve it in a sanitary condition and furthermore to provide a table. For this purpose, the present top or cover consists of a sheet of galvanized iron 11, which in the present disclosure is illustrated rectangular to correspond to a similarly shaped tub. This sheet of metal 11 is rectangularly notched at each corner for a short space, with the resultant intervening wings 12 and the marginal portion of each of these wings is rolled 65 into tubular formation as shown at 13.

After formation of the tubular rolls, the remainder of each wing is bent over to lie against the under side of the adjacent portion of the sheet 11 and with the tubular rolls 70 13 all against the sheet and with their ends meeting so that they jointly constitute a rectangular, cross sectionally tubular flange that depends from the bottom of the sheet and this rectangular flange in the use of the 75 cover fits within the enclosure of the upper edges of the walls of the tub. It will be noted that the tubular rolls have their outer sides flattened and at obtuse angles to the under faces of the folded wings 12, so that 80 the continuous flange will wedge into the opening of the tub and thus prevent lateral movement of the cover on the tub.

Where the side edges of the notched portions of the sheet come together when the 85 wings are folded as above described, the edges are soldered so as to prevent access of moisture to the iron and the meeting ends of the tubular rolls, which are mitered and mutually contacted, are likewise soldered 90 and for the same purpose as well as to give durability to the structure.

To give rigidity, the central portion of the sheet is pressed downwardly, as shown at 14, with a resultant wall 15 connecting 95 the depressed portion with the remainder and at obtuse angles to both. When desired, further stiffening means may be employed consisting of two straps of metal 16 and 17 that are disposed one upon the other at right 100 angles, with their extremities engaged between the corresponding tubular rolls 13 and the body of the sheet, where they are secured. They not only give rigidity to the sheet, but assist in sustaining the tubular 105 rolls. Where the two straps 16 and 17 cross, a rivet 18 is passed through them and through the sheet while an additional rivet 19 is engaged through each wing 12 beyond its tubular roll, through the body of the 110

sheet and through the corresponding end of a strap that enters therebetween.

Instead of removing the cover from the tub when the latter is to be used, it is preferred at times to raise the cover with a hinging movement so that its upper edge may lean against a wall or other support and in order that the bottom edge of the cover at such times may rest immovably on the upper edge of the tub, there are provided a pair of hook plates 20 that are connected by means of chains 22 and rivets 23, to the body of the cover, slightly inwardly from one of the rolls 13. These hooks are engaged downwardly over the upper edge of the rear wall of the laundry tub as shown in Figure 3. The chains permit the cover to be placed in closing position and also permit it to be raised to the position in Figure 3, at which time the lower edge of the cover will be prevented from sliding forwardly along the upper edges of the side walls of the tub by contact of the lower edge portion of the cover with the chain.

It will be understood that in practice any desired materials, dimensions and proportions may be used, while the simplicity, the economy of production and the durability of the article, will be appreciated.

What is claimed is:

1. A cover for laundry tubs comprising a sheet metal plate having its corners notched and the resultant wings provided with integral tubular end portions, the wings extending at an angle from the under face of the sheet with the tubular portions depending therefrom and in terminal contact therewith to produce a continuous flange, said tubular portions lying inwardly of and in parallel relation with the marginal edges of the cover, the outer face portions of the tubular portions being inclined for wedging action with the walls of a tub.

2. A cover for laundry tubs comprising a sheet metal plate having its marginal portions folded and extending at an angle from its under side and with the edges of the marginal portions in tubular form, and reinforcing bars extending transversely of the plate with their ends secured within the folded marginal portions of the cover.

In testimony whereof, I affix my signature in the presence of two witnesses.

LEO HIRSCHBERG.
